UNITED STATES PATENT OFFICE

2,147,839

BASIN FITTING

Andrew T. Hagerty, Elkhart, Ind., assignor to The
Adlake Company, a corporation of Illinois

Application December 31, 1936, Serial No. 118,619

5 Claims. (Cl. 4—195)

The present invention relates to wash basins of the type commonly employed in railway passenger cars and has as its principal objects the following: To provide a housing which effectively seals the opening above the faucet and drain equipment; to provide a housing which is adapted to carry the faucet and valve operating levers, but at the same time having a smooth, regular outer surface; to provide a combination housing and lever assembly in which the levers are quickly and easily secured to the housing in proper alignment; to provide a housing having the above characteristics and in addition one affording a smooth covering for the water spout; and to provide a housing which is devoid of cracks and seams so as to minimize the opportunity for dirt to accumulate.

Further and other objects and advantages will become apparent as the disclosure proceeds and the description is read in conjunction with the accompanying drawings, in which

Fig. 1 is a plan view of a preferred form of the basin fitting showing it installed on a basin;

Fig. 2 is an enlarged vertical sectional view of the basin fitting taken on the line 2—2 of Fig. 1 through a water faucet;

Fig. 3 is an enlarged vertical sectional view taken on the line 3—3 of Fig. 1 and showing the complete drain assembly;

Fig. 4 is a plan view of a modified form of the invention mounted on a sheet metal basin and showing the housing provided with an extension for covering the spout;

Fig. 5 is an end elevational view of the form shown in Fig. 4 with the metal basin in section and showing the method of securing the faucets to a metal basin;

Fig. 6 is an enlarged vertical sectional view taken through the center lines of the faucets on the line 6—6 of Fig. 1;

Fig. 7 is a vertical sectional view taken through the spout on the line 7—7 of Fig. 3 and showing the means for securing the spout to the basin;

Fig. 8 is an enlarged bottom plan view of the housing and lever attachment shown in Fig. 6 illustrating how the levers are secured to the housing; and

Fig. 9 is a vertical sectional view taken on the line 9—9 of Fig. 6.

Particular embodiments of this invention are chosen only for the purpose of illustration and description as required by Sec. 4888 of the Revised Statutes and the appended claims are not intended to be limited thereby but are to be con-

structed as broadly as the state of the prior art will permit.

Referring now to the figures:

The reference character 15 represents a wash basin of the type generally used in railway passenger cars which includes a bowl 16 and a slab 17 having a flange 22 for securing the basin to the wall. An elongated opening 18 (Fig. 1), is provided for receiving the usual hot and cold water faucets 19 and 20 respectively and the drain 10 operating mechanism generally indicated at 21.

A housing 25 being of such shape and proportions as to extend beyond the dimensions of the opening 18 rests on the surface of the wash basin 15. The open side of the housing is bounded by a flange 26 having a groove 55 for receiving a quantity of sealing compound such as putty 27 so that the opening 18 may be effectively sealed on the upper surface of the basin. Through the top face of the housing 25 apertures 28, 29 and 30 are provided to receive the hot water lever 31, the drain lever 32 and the cold water lever 33, respectively. These levers are pivoted to the housing which in turn is secured in place by means of bolts 34 and 35 threaded into the faucet and drain casting at 23 and 24 respectively.

The levers 31, 32 and 33 are provided with fulcrum openings to receive a shaft 56 as shown in Figs. 8 and 9 and the shaft in turn is received by a number of slots 57 in the projections 30 58 extending inwardly from the inner face of the housing 25. The purpose of the slots is to properly align the shaft with reference to the apertures 28, 29 and 30 and obviously the results can be obtained by other means, such, for example, as a plurality of lugs spaced longitudinally of the housing and adapted to act as guides for aligning the shaft 56.

A number of washers 59 are secured to the projections 58 by means of bolts 60 threaded into the projections as shown in Fig. 9, these washers being so shaped that they extend over the shaft 56 securing the same to the housing. The hot and cold water levers are held in closed position by means of springs 61 and 62 which surround the shaft 56 and engage the lower portion of the levers as shown at 63 and the inner face of the housing at 64. This method of securing the levers to the housing is especially adaptable to use in a railway passenger car since the assembly is easily mounted on a basin and always readily removable; and furthermore, the substantial lack of cracks and seams is a great aid to maintaining cleanliness.

Referring to Fig. 2, reference character 36 indicates a faucet body of the usual type being 55

threaded at its lower end to receive a water pipe 37 and containing a valve body 38 having a valve seat 39 at its lower extremity, a valve cap 40 and a valve spring 41 for urging the valve cap against the valve seat 39. The valve is operated by means of the lever 33 through a valve stem 42 which is threaded into a valve cap 40 as shown at 43 and a washer 44 is inserted between the valve stem and the valve seat. The cap 40 is provided with the usual washer 45. The valve body 38 is screwed into the faucet body as shown at 46 and is forced into a resilient washer 47.

As shown in Fig. 3 the hot and cold water faucets discharge into a port 48 which extends longitudinally of the casting comprising the faucet and drain and the water discharges through a single spout 49 into the bowl 16.

This spout is secured to the faucet casting by means of bolts 65 and 66 as shown in Fig. 7 and a washer 67 is provided to prevent leaks.

The bowl is provided with the usual drain 50 extending downwardly from a hole 51 in the lower portion of the bowl and comprises broadly a drain valve 52 operated by a drain lever 32 through a series of links, shafts and yokes generally indicated at 54.

The drain operating mechanism consists of a flexible shaft 70, one end of which is secured to a lever plunger 71 which engages a yoke 72, and the other end of which is secured to a lever stem 73, the flexible shaft being enclosed in a casting 74. Screw caps 65 and 66 provided with washers 67 are employed to seal the upper and lower ends of the casing, respectively. A lever link 75 at one end is pivoted to the operating lever 32 as shown at 76, and at the other end is pivotally secured to the stem 73 as shown at 77. The entire drain operating mechanism, consisting of the drain lever 32, the link 75, stem 73, shaft 70 and the plunger 71, is removable as a unit by merely removing the housing and lever assembly 25.

The yoke 72 is pivoted to the drain body 50 at 78 and is so designed as to be received by the aperture 79 in the stem 80 of the drain valve 52. As is readily seen in Fig. 3, when the lever 32 is moved to the left a force is applied through the series of links and shafts to the yoke 72 so as to raise the left hand arm of the yoke 72 thus lifting a valve 52 from its seat. On reversal of the lever, the valve is reseated. The drain body 50 is inserted in the bowl opening 51 and is sealed in place by means of a gasket 81 forced against the bottom of the bowl when the drain body is screwed into the bowl flange 82.

The casting comprising the hot and cold water faucets 19 and 20 is provided with flanges 83 and 84 which engage the sink slab 17 as shown in Fig. 6. A pair of brackets 85 adapted to engage the under side of the slab 17 are employed to secure the castings to the basin, and cooperate with the flanges 83 and 84 to act as clamps when the bolts 86 and 87 are drawn up into the casting.

As shown in Fig. 6 the faucets are secured to a basin of vitreous material which necessarily is

of greater thickness than that required of a metal basin but obviously this invention is applicable equally well to a metal basin as shown in Fig. 5. For this purpose it is necessary to use a pair of brackets of the type shown at 88 having a U section rather than the flat plates shown in Fig. 6. The application of these brackets is no different, however; they serve the same purpose as do brackets 85.

The housing 25 may be of a variety of shapes as for example, elongated as shown in Fig. 1, with a cut-out portion 89 to fit around the spout 49, or as shown in Figs. 4 and 5, the housing may be provided with an extension 90 adapted to shield the spout 49 from view, resulting in giving a pleasing appearance and providing a cover which is devoid of cracks and seams. This latter form is especially advantageous as it has all of the favorable characteristics of the form shown in Fig. 1 and in addition minimizes the opportunity for the accumulation of dirt.

I claim as my invention:

1. An elongated housing having a plurality of apertures through its upper face, a plurality of inwardly extending projections along its inner face, a U-shaped slot in each projection a valve operating lever extending from each of the apertures and having a fulcrum opening, a shaft extending through the fulcrum openings of the levers and recessed in the slots, and a plurality of springs surrounding the shaft and each arranged to engage a lever so as to urge it into the closed position of the valve.

2. A basin slab, an opening in the slab, a faucet body in the opening having a flange extending therefrom for engaging the top of the slab, a bracket for engaging the lower surface of the slab, means for securing the bracket to the faucet body, a housing for covering the opening, and means for securing the housing to the faucet body.

3. A housing having an aperture in its upper face, a lever extending from the aperture and having a fulcrum opening, a shaft inserted in the fulcrum opening, a plurality of notched projections spaced along the inner face of the housing for receiving the shaft, and means for holding the shaft in such notches.

4. An elongated housing having a plurality of apertures in its upper face, a plurality of lugs spaced along its inner face, a lever extending from each of the apertures having a fulcrum opening, a shaft extending through the fulcrum openings of the levers and held in alignment with the apertures by the lugs, and means for securing the shaft in such alignment.

5. A housing, a lever, and means for securing the lever to said housing including a shaft and a plurality of lugs spaced along the inner face of the housing for alining the shaft, and means for intermediate the lugs for holding the shaft in place.

ANDREW T. HAGERTY.
